UNITED STATES PATENT OFFICE

GEORGE W. VEALE, OF CLEVELAND HEIGHTS, OHIO, ASSIGNOR TO EATON MANUFACTURING COMPANY, OF CLEVELAND, OHIO, A CORPORATION OF OHIO

DESIGN FOR AN IMPACT BAR FOR AUTOMOBILE BUMPERS

Application filed December 17, 1931. Serial No. 42,121. Term of patent 3½ years.

To all whom it may concern:

Be it known that I, GEORGE W. VEALE, a citizen of the United States, residing at Cleveland Heights, in the county of Cuyahoga and State of Ohio, have invented a new, original, and ornamental Design for Impact Bars for Automobile Bumpers, of which the following is a specification, reference being had to the accompanying drawing, forming a part thereof.

In the drawing,

Figure 1 is a front elevation of an impact bar embodying my improved design; and

Fig. 2 is a plan view thereof.

The ornamental design in an impact bar for automobile bumpers, as shown, consists of a longitudinally arched bar having a transversely curved front face, the radius of curvature decreasing from the central portion of the bar toward the opposite ends and the depth of the bar tapering from the central portion toward the ends.

I claim:

The ornamental design for an impact bar for automobile bumpers, as shown and described.

GEORGE W. VEALE.
